UNITED STATES PATENT OFFICE.

CHARLES EDWARD JAMES AND WILLIAM EDWIN SMITH, OF WAVERLEY, NEAR SYDNEY, NEW SOUTH WALES, AUSTRALIA.

CONVERTIBLE FURNITURE.

1,413,279.

Specification of Letters Patent. Patented Apr. 18, 1922.

Application filed October 25, 1920. Serial No. 419,432.

To all whom it may concern:

Be it known that we, CHARLES EDWARD JAMES and WILLIAM EDWIN SMITH, subjects of the King of Great Britain and Ireland, residing at 88 Cowper Street, Waverley, near Sydney, New South Wales, Australia, have invented certain new and useful Improvements in Convertible Furniture, of which the following is a specification.

10 This invention relates to convertible furniture and has for its object to provide an article of furniture which may be converted for use either as a lounge, a bedstead, an easy chair, or a deck chair, and which may under 15 certain occupations thereof be also provided with separate rest seats or tables or with a rest seat and a table.

The invention is illustrated in the accompanying drawings, in which Fig. 1 is a perspective view of the article of furniture erected for use either as an easy chair or a deck chair and with a table and a rest seat; Fig. 2 is a cross section of the furniture illustrated in Fig. 1; Fig. 3 is a perspective view of the article of furniture erected for use either as a bedstead or a lounge; and Fig. 4 is a cross section of the furniture shown in Fig. 3.

The furniture consists of foldable side 30 portions 1 and 2 which are hinged to each other at 3 and may be extended as shown in Fig. 3 or folded against each other when the seats or tables 4 and 5 have been removed therefrom. Located between the side portions 1 and affixed thereto is the box or recess 35 7 having a cover 6 hinged at 20 to said box. At the forward and rear ends respectively of the box 7 are the extension pieces 8 and 9 which are hinged to the front and rear walls 40 of the box at 10 and 11; said extension pieces respectively carry supporting legs 12 and 13 hinged at 14 and 15 and foldable on to said extensions. The tables or seats 5 and 4 are detachable from the side portions 1 and 2; 45 they carry suitable hook fastenings 16 capable of engaging the rails of the said side portions and are interchangeable for use thereon either as a pair of tables or as a pair of rest seats, or as a single table and a 50 single rest seat as shown in Fig. 1. Said tables are removed from the side portions 1 and 2 when it is desired to utilize the furniture either as a lounge or as a bedstead as shown in Fig. 3. Hook and eye fastenings 24 55 are respectively attached to the legs 12 and 13

and the extension pieces 8 and 9 to enable such legs and extension pieces to be securely held to each other when the legs are erected in their support position.

Attached to the heads of each of the rear 60 posts 17 of the side portions 1 is a pin 18; each of these pins carries a chain 19 adapted to be secured to the extension piece 9 at both sides thereof. These chains may depend from said pins 18 or their links may be secured to the extension piece 9, in which event the said extension piece may be used as a back or head rest for a person occupying the central portion 6 of the furniture as a 65 rest seat.

When the legs 12 are folded to the extension piece 8, the latter may be closed within the box 7 upon raising the cover 6 thereof. Similarly, when the chains 19 are detached from the extension piece 9 the latter may be 70 made to overfold on the cover 6 of the box 7.

At the back of the extension piece 9 to the rear and at either side thereof is a catch 21 consisting of a metal plate bent to L-shape and on the posts 22 of the side portions 2 are 80 eyes 23. The said eyes are positioned on the posts 22 to enable them to be engaged by the catches 21 on the extension piece 9 when the furniture is erected for use as a lounge or a bedstead and the said extension piece is 85 lying in horizontal position as shown in Figs. 3 and 4.

If the rest seats or tables 4 and 5 are detached from the furniture the foldable side portions 1 and 2 may be juxtaposed. The 90 furniture is then usable as an easy or a deck chair without side tables or seats. In Fig. 1 the side portions 2 are shown in angular relation to the side portions 1 and a rest seat 4 is set between one pair of said side portions whilst a table 5 is set between the other pair of said side portions. If the furniture is to be used as a chair, the extension piece 8 may be set on a support as shown in Fig. 1, the folding legs 12 hinged to the extension 95 8 resting on the support. The extension 8 may, however, be closed within the box 7 by folding the legs 12 on the extension 8 and raising the cover 6 to enable the said extension to be enclosed within the box 7 if the 100 furniture is to be used as a chair.

In case the furniture is to be used as a bedstead or a lounge, the chains 19 are detached from the extension piece 9 and the side portions 2 are swung on the hinges 3 to bring 110

the side portions 1 and 2 into alignment as shown in Fig. 3 the catches 21 engaging the eyes 23 when the extension piece 9 is lowered to horizontal position. The extension piece 8 is also set in erect position as shown in Fig. 3 with its legs 12 resting on a support. Similarly the legs 13 are set to support the extension piece 9.

Cushions or mattresses of any approved type may be used in connection with the furniture when it is being used either as a rest chair or as a bedstead or lounge. The furniture is constructed of wood to any preferred pattern. Cushions may be stored in the box 7 when they are not in use.

What we claim as our invention and desire to secure by Letters Patent is:—

Convertible furniture of the type herein described comprising a pair of stationary side frames, a box carried by said frames, a cover for said box hinged to the rear wall of the box, a rigid foot extension of less length than said box having its rear end hinged to the front wall of said box, said extension being foldable into said box, sup-

porting legs of a length equal to the distance from the bottoms of said frames to the upper edge of the front wall of said box; a hinge connecting said legs to the front end of said first mentioned extension to permit the legs to assume positions at right angles to or parallel with said foot extension, a pair of movable frames hinged to said stationary frames and adapted to be folded against the outer sides of said stationary frames, a back extension hinged to said box, means carried by said movable frames for connecting the back extension to said movable frames, means for supporting said back extension in an inclined position, and an auxiliary back extension support of the same length as the legs hinged to said back extension and capable of assuming positions at right angles to and parallel with said back extension.

In testimony whereof we affix our signatures.

CHARLES EDWARD JAMES.
WILLIAM EDWIN SMITH.
